Primary Examiner — Susan Bennett Hattan*Assistant Examiner* — Jennifer Campbell(74) *Attorney, Agent, or Firm* — Wood, Herron & Evans, LLP**CLAIM**

The ornamental design for a timer cover, as shown and described.

DESCRIPTION

FIG. 1 is a perspective view of a timer cover illustrating our new design;

FIG. 2 is a rear perspective view thereof;

FIG. 3 is a front view thereof;

FIG. 4 is a right side view thereof, the left side being a mirror image thereof;

FIG. 5 is a rear view thereof;

FIG. 6 is a top view thereof; and,

FIG. 7 is a bottom view thereof.

Any elements shown in broken lines form no part of the claimed invention, and are instead included to show environmental aspects of the claimed invention.

1 Claim, 3 Drawing Sheets---
